UNITED STATES PATENT OFFICE.

EWALD KOERNER, OF DRESDEN, GERMANY.

SHEET-FEEDING DEVICE.

1,072,397.

Specification of Letters Patent.

Patented Sept. 2, 1913.

Original application filed June 15, 1912, Serial No. 703,871. Divided and this application filed July 16, 1913. Serial No. 779,320.

To all whom it may concern:

Be it known that I, EWALD KOERNER, a subject of the Emperor of Germany, residing at Dresden, Germany, have invented 5 new and useful Improvements in Sheet-Feeding Devices, of which the following is a specification.

The present invention, which is a division of my copending application Serial 703,871, filed June 15, 1912, relates to a device for feeding sheets of paper from the bottom of a pile, and includes the provision of a frame which is so arranged under the paper pile that it can be reciprocated from one 15 end to the other of the same. Mounted in bearings carried by said frame are two rollers which alternately support the paper pile by means of flexible bands each having one end connected to one of the rollers and the 20 other end to a stationary element, the arrangement being such that one roller as it passes beneath the pile of sheets is rotated by said pile when the frame is reciprocated in one direction and winds a band around 25 its circumference while the other roller unrolls its band previously wound thereon. The rollers are each fitted with suction nozzles or mouths by means of which they successively pick a sheet from alternate ends 30 of the pile and discharge it between rollers.

In the accompanying drawings illustrating the preferred form of the invention; Figure 1 is a vertical sectional view of the invention showing the parts in one extreme 35 position. Fig. 2 is a similar view showing the same parts in the other extreme position, and Fig. 3 is a plan view.

In the drawing, a frame 1 is arranged to reciprocate to and fro in a guide-way 13 40 under a pile of sheets 12, supported alternately by rollers 3 and 4 mounted to oscillate in bearings connected to the frame 1 and which roll against the under-surface of the pile when the frame is reciprocated. 45 Fastened to the roller 3 is one end of a flexible band 5, the other end of which is connected to a stationary element 7, the arrangement being such that as the frame 1 reciprocates, the roller 3, bearing against 50 the under side of the pile 12, is rotated and the band 5 wound thereon when the frame is moved in one direction, and unrolled beneath the pile to form a support therefor, as shown in Fig. 2, when the frame moves 55 in the opposite direction. A second band 6

is connected in the same manner to the roller 4 and is also fastened to a stationary element 8. When one band is wound upon its roller, the other band is unrolled for supporting the pile, the position being reversed for each movement of the frame 1. 60

Each roller is provided with a suction device comprising a plurality of suction mouths or nozzles 11 opening through the periphery of the roller in a longitudinal 65 row just along the fastened edge of the band. These mouths or nozzles 11 in the rollers communicate through the body of each roller with its hollow shaft 9, said shafts being connected by flexible pipes 14 70 with any appropriate suction means, not shown, by which a vacuum or partial vacuum is created in the suction devices.

The parts are so arranged that when the frame 1 is in one extreme position as in Fig. 75 1, the band 5 will be wound around the roller 3 and the latter be beyond the pile 12. The band 6, however, supports the pile of wrappers and the suction nozzles 11 of the roller 4 abut against the left end of the 80 paper pile 12 so as to suck that end of the lowermost sheet against the roller. As the frame 1 travels to the right, the weight of the pile 12 on the roller 4 turns said roller in the direction of the arrow to wind the 85 band 6 thereon and carry the sheet with it, removing said sheet from the bottom of the pile and feeding it between the rollers, the suction being interrupted at the right moment and the sheet discharged. This same 90 movement of the frame 1 unwinds the band 5 from the roller 3 and carries the band 5 under the pile 12 to support it when the band 6 has been wholly wound on the roller 4 and passed from beneath the pile 12, as 95 in Fig. 2. The suction mouths or nozzles 11 of roller 3 are now immediately below the right end of the pile 12 and suck that end of the lowermost sheet against the mouths. The frame 1 being now moved to the left 100 105 the band 5 is wound on roller 3 and band 6 unwound from roller 4, the roller 3 drawing the bottom sheet of the pile from the pile and delivering it between the rollers as before. It will thus be evident that a sheet will be delivered at each reciprocation of the frame 1, being picked from alternate ends 110 of the pile and carried between the rollers. A bracket or abutment 10 is provided for the edges of the sheets to hold them in place.

What I claim is:—

1. In a device for feeding single sheets from a pile of sheets, means for supporting said pile of sheets and adapted to reciprocate beneath the same and successively pick single sheets from the bottom and alternate ends thereof.
5
2. In a device for feeding single sheets from a pile of sheets, means for supporting said pile of sheets and adapted to reciprocate beneath the same, and pneumatic means movable with the reciprocating supporting means for successively picking single sheets from the bottom and alternate ends of said pile.
10
3. In a device for feeding single sheets from a pile of sheets, means for supporting said pile of sheets and adapted to reciprocate beneath the same, and alternately operated suction means movable with said reciprocating supporting means for successively picking single sheets from the bottom and alternate ends of said pile.
15
4. In a device for feeding single sheets from a pile of sheets, means for supporting said pile of sheets and adapted to reciprocate beneath the same, a pneumatic suction means movable with the reciprocating supporting means for picking a sheet from the bottom of said pile at one end when traveling in one direction, and a second pneumatic suction means for picking the successive sheet from the bottom of the pile at the other end when traveling in the opposite direction.
20
5. In a device for feeding single sheets from the bottom of a pile of sheets, a reciprocating frame, a pair of rollers rotatably mounted in said frame, each roller having a peripheral suction mouth, two flexible bands each fastened at one end to a roller adjacent the suction mouth thereof, and at
25
6. In a device for feeding single sheets from a pile of sheets, a reciprocating frame, a pair of rollers mounted thereon to oscillate as said frame moves to and fro beneath a pile of sheets, a suction means having a mouth opening through the periphery of each roller to successively pick single sheets from the bottom of said pile and from alternate ends thereof, and a flexible band attached to each roller adjacent the suction mouth and to stationary elements said bands alternately winding upon and unwinding from said rollers as the frame reciprocates.
30
7. In a device for feeding single sheets from a pile of sheets, a reciprocating frame, a pair of rollers mounted thereon to oscillate as said frame moves to and fro beneath a pile of sheets, two flexible bands for supporting said pile of sheets, each attached at one end to a stationary element and extending toward each other and fastened by their other ends to the respective rollers to be wound thereon and unwound therefrom as the frame reciprocates, and a suction means having a mouth opening through the periphery of each roller to successively pick single sheets from the bottom of said pile and from alternate ends thereof and deliver them between said rollers.
35

In testimony whereof I have hereunto set my hand in presence of two subscribing witnesses.

EWALD KOERNER.
